UNITED STATES PATENT OFFICE.

MARION J. BUCEY AND HAROLD O. BUCEY, OF REDONDO, WASHINGTON.

CLOTHES-DRIER.

1,112,765.

Specification of Letters Patent.

Patented Oct. 6, 1914.

Application filed January 9, 1913. Serial No. 741,057.

To all whom it may concern:

Be it known that we, MARION J. BUCEY and HAROLD O. BUCEY, citizens of the United States, residing at Redondo, in the county 5 of King and State of Washington, have invented a new and useful Clothes-Drier, of which the following is a specification.

This invention relates to devices to hang clothes on while they are drying and has 10 especial reference to devices adapted to domestic use.

The objects of our invention are to provide a device which is removably attached to and supported by the hot water tank or 15 boiler; in which the rods may be placed in any position around the tank; and in which the rods not in use may be folded down out of the way. We attain these and other objects by the devices and arrangements illustrated in the accompanying drawings in 20 which—

Figure 1 is a perspective view of the tank showing our device applied thereto; Fig. 2 is a plan of the device, the tank being 25 shown in section; Fig. 3 is a vertical section through the supporting band showing the rod in position for use; Fig. 4 is a similar view showing the rod folded down; and Figs. 5 30 and 6 are plans of the rod carrier showing the rod in its two positions.

Similar numerals of reference refer to similar parts throughout the several views.

This device is intended to be secured to 35 the hot water tank, thereby bringing the clothes under the influence of the heat radiated from the hot water therein. The tank 1 may be of any of the usual vertical kinds now in use. A band 2 passes around 40 the tank, one end being preferably turned back and riveted on itself to form a loop 3, while the other end is turned outward to form a flange 4. One or two bolts 5 pass through the flange 4 and the loop 3, engaging 45 suitable nuts by means of which the ends are drawn toward each other to clamp it to the tank 1.

The upper and lower edges of the band 2 are bent over outward to form guides 15 extending the entire length of the band except 50 for a short space near one end. The guides 15 form channels around the tank 1, said channels being parallel and of such dimensions as to hold and guide the carriers 6

which are free to slide therein to any position around the tank. The carriers 6 are inserted between the guides 15 at the above mentioned end space and are preferably made of cast metal and each consists of a back plate, which is slightly concave in 55 form, as at 7, to fit the curvature of the band around the tank; a pair of bracket arms 8, which extend out from the back plate; and a lug 9, which is over and adjacent one of the arms 8 and extends a short distance out 60 from the back plate but which only reaches about one-half way between the arms 8, thus leaving an open space between it and the other arm. A rod 10 is loosely secured to the carrier by a pin 11 which passes through 65 it near one end and which is secured across the bracket arms 8. The rod 10 can slide freely on the pin 11 and can also turn about it. When the rod is on the left end of the pin, it can swing freely on the rod because 70 its end does not engage the lug 9, but when it is placed horizontally and pushed over to the right end of the pin it cannot move downward because its end will then be under the lug 9 and will prevent the outer end of the 75 rod from passing downward. In order to fold the rod it is only necessary to push it on the pin toward the left until its end passes from under the lug 9 when it is free to turn and can be folded down. 85

It is evident that when this device is not in use the carriers may be pushed back of the tank, which is generally placed near the wall of the room, and thus are completely removed from sight and cannot be in the way, 90 while if one rod is needed, the nearest carrier may be slid out from behind the tank and placed in a more desirable position and its rod may then be swung up to horizontal position and held in that position as above 95 described. Additional carriers may be brought out from behind the tank as needed.

Having therefore described our invention, what we claim is:—

In a clothes drier, the combination with a 100 band removably clamped to a supporting tank; integral flanges formed on the upper and lower edges of said band and forming parallel guide channels therewith around the tank; carriers supported by and slidable 105 in said guide channels; a pair of brackets extending out from each carrier; a pin joining the brackets of each pair; a rod loosely

mounted on said pin and slidable therealong; and a lug formed on the carrier adjacent one of the brackets thereon and leaving an open space between it and the other bracket whereby when said rod is slid under said lug it is held in extended horizontal position but when it is slid under said open

space it is free to turn on the pin and lie in vertical folded position.

MARION J. BUCEY.
HAROLD O. BUCEY.
